[57] CLAIM

The ornamental design for a water closet, as shown and described.

DESCRIPTION

FIG. 1 is a front elevational view of a water closet embodying my new design;

FIG. 2 is a top plan view thereof;

FIG. 3 is a left side elevational view thereof, the right side elevational view being a mirror image of the left side shown; and,

FIG. 4 is a cross-sectional view taken along line 4—4 of FIG. 2.

The broken line representations of holes in FIG. 2 and of mounting hardware in FIG. 3 are for the purpose of illustration only, and form no part of the claimed design.
